UNITED STATES PATENT OFFICE

138,010

DESIGN FOR AN ALPHABET FOR FORMING MONOGRAMS OR SIMILAR ARTICLE

Nicholas Barbieri, Providence, R. I., assignor to Uncas Manufacturing Company, a corporation
of Rhode Island

Application March 16, 1944, Serial No. 112,915

Term of patent 14 years

(Cl. D64—1)

To all whom it may concern:

Be it known that I, Nicholas Barbieri, a citizen of the United States, residing in Providence,
county of Providence, and State of Rhode Island,
have invented a new, original, and ornamental
Design for an Alphabet for Forming Monograms or Similar Article, of which the following is a specification, reference being had to the accompanying drawing, forming a part thereof.

Figure 1 is a face view of the letters of the alphabet showing my design;

letter "A"; and

letter "A" being a typical example.

I claim:

The ornamental design for an alphabet for forming monograms or similar article, substantially as shown.

NICHOLAS BARBIERI.
